UNITED STATES PATENT OFFICE

135,339

DESIGN FOR A SLIPPER

Harry E. Hanson, St. Paul, Minn.

Application June 25, 1942, Serial No. 107,338

Term of patent 3½ years

To all whom it may concern:

Be it known that I, Harry E. Hanson, a citizen of the United States, residing at St. Paul, county of Ramsey, and State of Minnesota, have invented a new, original, and ornamental Design for a Slipper, of which the following is a specification, reference being had to the accompanying drawing, forming part thereof.

My design for a slipper, of the configuration as shown, is characterized by the sole which is flat throughout most of its length but turns upwardly at the toe.

I claim:

The ornamental design for a slipper, as shown and described.

HARRY E. HANSON.
